SCREEN TENSIONING TOOL

Virgil L. Esrey, Memphis, Tenn.

Application July 25, 1955, Serial No. 524,150

6 Claims. (Cl. 146—109)

This invention relates to a tool for tensioning screen wire on a frame or the like. In particular it relates to such a tool having improved means for tensioning said screen wire, said means being adjustably secured to a handle whereby said tool may be adjusted for various size frames.

In tensioning or stretching screen wire on a frame as a window or door frame it is common practice to secure the screen to one side of the frame and to tension or stretch the screen across to the other side for securing thereto while under tension.

The present invention is directed towards providing an improved tool for performing this tensioning or stretching operation and for holding the stretched screen while being secured to the frame.

It is further directed towards providing a tool having a pair of screen-engaging hooks spaced apart to provide accessibility for securing the screen near and between said screen-engaging hooks.

It is further directed towards providing such a tool which is characterized by efficiency of operation yet has simplicity of construction.

The principal object of the present invention is to provide an improved tool for tensioning screen wire on a frame or the like.

A further object is to provide such a tool having an improved screen-engaging member, said screen-engaging member having a pair of spaced hooks adapted to engage the screen wire.

A further object is to provide such a tool having a body member provided with a plurality of transversely extending and longitudinally spaced slots, said slots being adapted to removably receive the end of said screen-engaging member, whereby said tool may be adjusted to fit various sizes of frames.

A further object of the invention is generally to improve the design, construction and efficiency of screen tensioning tools.

The means by which the foregoing and other objects of the present invention are accomplished and the manner of their accomplishment will be readily understood from the following specification upon reference to the accompanying drawings, in which:

Fig. 1 is a plan view of the screen-engaging member of the tool of the present invention.

Fig. 2 is an elevational view of the body member of the tool of the present invention.

Fig. 3 is a plan view of the assembled tool illustrating the position of the tool after tensioning of the screen.

Fig. 4 is an elevational view, with parts broken away for purposes of illustration, of the tool illustrating in solid lines the tool in screen engaging position before tensioning and illustrating in dotted lines the position of the tool after tensioning of the screen.

Referring now to the drawings in which the various parts are indicated by numerals, the tool embodying the present invention comprises in general a body member

2

11 to which is removably attached a screen-engaging member 13.

Body member 11 preferably comprises a handle 15 of inverted channel shape having a top 17 and a pair of spaced sides 21 depending from opposite edges of top 17. Body member 11 includes a depending abutment portion 23 at one end thereof. The forward face 25 of abutment portion 23 is preferably disposed substantially perpendicular to the longitudinal axis of handle 15. For adding strength to the structure of body member 11 the lower edges of sides 21 may be turned inwardly as at 26.

Body member 11 is provided with a plurality of longitudinally spaced slots 27 adapted to be engaged by screen-engaging member 13. Slots 27 are preferably formed by cutting substantially equal transverse segments out of the material of top 17 at equally spaced intervals and extending the portions thus cut out downwardly through the upper portion of sides 21. Thus it will be understood a plurality of equally spaced transverse U-shaped slots 27 are formed with the cutout portion thereof in sides 21 being substantially perpendicular to top 17.

A pair of lugs 29 respectively extend outwardly from the opposite sides of abutment portion 23 adjacent but rearward of face 25 and are adapted to embrace and engage portions of screen-engaging member 13. Each of lugs 29 may be integrally formed from abutment portion 23 by making a U-shaped cut in the material of the abutment portion 23 and outwardly bending the free end thus cut out. It will be apparent that lugs 29 may be otherwise formed, as for example lugs 29 may comprise a pair of pins or other abutment means. Lugs 29 are preferably spaced from top 17 whereby screen engaging member 13 will be held in a position intermediate the upper end and the lower end of the forward face 25 of abutment portion 23.

Screen-engaging member 13 may comprise a pair of elongated rod like fingers 31 joined at one end by a slot engaging section, which preferably comprises a pair of loops 32 and a forwardly projecting U-shaped tip 33, the outward legs of the loops respectively joining the rear ends of fingers 31 and the inward legs of the loops being respectively joined by the legs of tip 33. It will be understood that said slot engaging section may otherwise be formed, as for example, the section may comprise a single loop and a forwardly projecting abutment means connected to said loop. Fingers 31 extend substantially parallel to one another along a major portion of their length and diverge toward their distal ends, whereby a flared out portion 35 of screen-engaging member 13 is formed. It will be understood from the description of the operation of the tool that the flared out portion 35, wherein the distal ends of screen-engaging member 13 are widely separated, will provide an accessible space for tacking the screen onto the frame without impairing the efficiency of operation of the tool.

55 The distal forward ends of fingers 31 are each provided with a hook 37 adapted to engage the screen wire 39 to be tensioned. Fingers 31 in addition to diverging in flared out portions 35 are also upwardly curved substantially in an arch. Hooks 37 preferably respectively extend downwardly and rearwardly from the distal ends of fingers 31 and terminate in a point. Screen-engaging member 13 may be formed integrally from a single piece of resilient wire with loops 32 and tip 33 being formed by doubling the wire forwardly. Loops 32 and tip 33 are preferably disposed in a plane inclined to and angularly intersecting the plane of the major portion of elongated fingers 31. Fingers 31 are preferably formed to slightly converge towards one another when disassembled from body

8655 8660 8665 8670 8675 8680 8685 8690 8695 8700 8705 8710 8715 8720 8725 8730 8735 8740 8745 8750 8755 8760 8765 8770 8775 8780 8785 8790 8795 8800 8805 8810 8815 8820 8825 8830 8835 8840 8845 8850 8855 8860 8865 8870 8875 8880 8885 8890 8895 8900 8905 8910 8915 8920 8925 8930 8935 8940 8945 8950 8955 8960 8965 8970 8975 8980 8985 8990 8995 9000 9005 9010 9015 9020 9025 9030 9035 9040 9045 9050 9055 9060 9065 9070 9075 9080 9085 9090 9095 9100 9105 9110 9115 9120 9125 9130 9135 9140 9145 9150 9155 9160 9165 9170 9175 9180 9185 919

engaging member 13 will be spread apart by body member 11 to a substantially parallel disposition and will be frictionally held onto body member 11 due to the resilient fingers being urged together.

In assembling the tool, handle 15 is inserted between the fingers 31 with flared out portions 35 extending downwardly. Tip 33 is then inserted in one of the desired slots 27 and the loops 32 respectively engaged with the opposite ends of the slot. It will be understood that the proper slot will be dependent upon the width of the frame upon which the screen wire is to be tensioned which will be more apparent from the later described operation of the tool. After tip 33 is inserted in one of the slots 27 fingers 31 are swung upwardly over abutment portion 23 into engagement with lugs 29 which limit further upward movement.

As best illustrated in Fig. 4, tip 33 will underlie a portion of top 17 forward of the slot in which tip 33 is inserted, whereby tip 33 limits upward movement of the rearward end of screen-engaging member 13 and prevents accidental removal of the screen-engaging member from slot 27. Upward travel of the forward end of screen-engaging member 13 is limited by lugs 29. Longitudinal movement of screen-engaging member 13 is limited by loops 32 being engaged with the ends of slot 27.

It will be understood that in the hereinabove described insertion of handle 15 between fingers 31, the fingers 31 will be spread apart slightly to conform to the thickness of handle 15 whereby screen-engaging member 13 will be frictionally held onto body member 11 as heretofore described. As will be apparent from the foregoing description, fingers 31 will respectively lie along opposite sides 21 of body member 11 substantially parallel with the longitudinal axis of the handle and flared out portions 35 will extend beyond the forward end of the body member.

In the operation of the tool the hooks 37 are engaged adjacent the free edge of a screen 39 which has previously been tacked along its opposite edge to a frame 41. The forward face 25 of abutment portion 23 is brought in abutment with the side edge 43 of frame 41 adjacent the lower edge of abutment portion 23 in a manner as best illustrated in solid lines in Fig. 4. The rearward end of handle 15 is then moved downwardly thereby sliding abutment portion 23 downwardly in respect to frame side edge 43; whereupon hooks 37 will move outwardly towards edge 43 and thereby tension screen 39. When handle 15 has reached a substantially horizontal position as illustrated in Fig. 3 and in dotted lines in Fig. 4, abutment portion 23 will be in substantially face to face engagement with side edge 43 of frame 41. Since the pull of the screen against the screen-engaging member 13 is substantially perpendicular to the face 25 of abutment portion 23, the tension of the screen 39 will hold abutment portion 23 in face to face engagement with side edge 43 and the handle 15 may be released if desired, thereby freeing the operator's hands for subsequent tacking of the screen as by tacks T. It will be understood that the spacing between hooks 37 is sufficient whereby the head of a hammer or other securing devices may move therebetween for securing the free edge of the screen to the frame 41. It will be understood that the screen tensioning tool may be disengaged from the frame 41 by upward movement of handle 15 and the tool may be placed at the next desired position for further securing the screen.

It has been found that the tool is most effective when the screen-engaging hooks 37 are placed in the vicinity of the tacking line. It is apparent that the hooks 37 may be positioned near the tacking line for different widths of frames by insertion of said slot engaging section in the proper slot 27 to give the desired distance between abutment portion 23 and hooks 37 which will be distance

corresponding to the distance from the side edge of the frame to the tacking line.

I claim:

1. A tool adapted for the tensioning of screen wire on a frame, comprising an elongated body member having a top and a pair of spaced sides depending from said top, said body member including a depending abutment portion at one end thereof, said abutment portion having an outer face which is disposed substantially perpendicular to the longitudinal axis of said body member and adapted to engage a frame, said body member being transversely slotted downwardly from the top thereof to form a plurality of longitudinally spaced slots extending transversely of said body member, a pair of lugs projecting from the opposite sides of said body member, a screen engaging member removably engaging said body member, said screen engaging member comprising a pair of spaced elongated fingers, each terminating in a hook adapted to engage screen wire, and a slot engaging section remote from said hooks joining said fingers at the rearward ends thereof, said slot engaging section being removably and selectively inserted in one of said slots whereby said screen engaging member is adjustable for various size frames, said slot engaging section comprising a pair of loops and a forwardly projecting U-shaped tip interposed therebetween; said loops being engaged with said body adjacent said one of said slots whereby longitudinal movement of said screen engaging member relative to said body member is limited and downward movement of the rearward end of said screen engaging member relative to said body member is limited, said tip underlying a portion of said top forward of said one of said slots whereby upward movement of the rearward end of said screen engaging member relative to said body member is limited, said spaced fingers respectively engaging said lugs whereby said lugs are effective to limit upward movement of said screen engaging member relative to said body member during the use of said tool for tensioning screen wire.

2. A tool adapted for the tensioning of screen wire on a frame, comprising an elongated body member having a top and a pair of spaced sides depending from said top, said body member including a depending abutment portion at one end thereof, said abutment portion having an outer face which is disposed substantially perpendicular to the longitudinal axis of said body member and adapted to engage a frame, the tops and sides of said body member being slotted downwardly from the top thereof to form a plurality of longitudinally spaced slots, stop means projecting from the opposite sides of said body member, a screen engaging member removably engaging said body member, said screen engaging member comprising a pair of spaced elongated fingers, each terminating in screen engaging means adapted to engage screen wire, and a slot engaging section remote from said screen engaging means joining said fingers at the rearward ends thereof, said slot engaging section being removably and selectively inserted in one of said slots whereby said screen engaging member is adjustable for various size frames, said slot engaging section comprising a pair of loops and a forwardly projecting U-shaped tip interposed therebetween, said loops being engaged with said body adjacent said one of said slots whereby longitudinal movement of said screen engaging member relative to said body member is limited and downward movement of the rearward end of said screen engaging member relative to said body member is limited, said tip underlying a portion of said top forward of said one of said slots whereby upward movement of the rearward end of said screen engaging member relative to said body member is limited, said spaced fingers respectively engaging said stop means whereby said stop means is effective to limit upward movement of said screen engaging member relative to said body member during the use of said tool for tensioning screen wire.

3. A tool adapted for the tensioning of screen wire on a frame, comprising an elongated body member having a top and a pair of spaced sides depending from said

top, said body member including a depending abutment portion at one end thereof, said abutment portion having an outer face which is disposed substantially perpendicular to the longitudinal axis of said body member and adapted to engage a frame, the tops and sides of said body member being transversely slotted downwardly from the top thereof to form a plurality of longitudinally spaced slots extending transversely of said body member, a pair of lugs projecting from the opposite sides of said body member, a screen engaging member removably engaging said body member, said screen engaging member comprising a pair of spaced elongated fingers, each terminating in a hook adapted to engage screen wire, and a slot engaging section remote from said hooks joining said fingers at the rearward ends thereof, said slot engaging section being removably and selectively inserted in one of said slots to engage said body whereby said screen engaging member is adjustable for various size frames, engagement of said slot engaging section with said body being effective to limit longitudinal movement of said screen engaging member relative to said body member and limit downward movement of the rearward end of said screen engaging member relative to said body member, said slot engaging section including a forwardly projecting abutment means, said abutment means underlying a portion of said top forward of said one of said slots whereby upward movement of the rearward end of said screen engaging member relative to said body member is limited, said spaced fingers respectively engaging said lugs whereby said lugs are effective to limit upward movement of said screen engaging member relative to said body member during the use of said tool for tensioning screen wire.

4. A tool adapted for the tensioning of screen wire on a frame, comprising an elongated, substantially channel shaped body member having a depending abutment portion at one end thereof adapted to engage a frame, the tops and sides of said body member being slotted downwardly from the top thereof to form a plurality of longitudinally spaced slots, stop means projecting from the opposite sides of said body member, a screen engaging member removably engaging said body member, said screen engaging member comprising a pair of spaced elongated fingers lying respectively along the sides of said body member, each terminating in a hook adapted to engage screen wire, and a slot engaging section remote from said hooks joining said fingers at the rearward ends thereof, said slot engaging section being removably and selectively inserted in one of said slots whereby said screen engaging member is adjustable for various size frames, said spaced fingers respectively engaging said stop means whereby said stop means is effective to limit upward movement of said screen engaging member relative to said body member during the use of said tool for tensioning screen wire.

5. In a tool for stretching screen wire, a substantially channel shaped body, having a top and depending sides, said top being slotted transversely of said body to provide a plurality of slots longitudinally spaced along said body, said sides being respectively slotted downwardly from said top through a part of the depth of said sides to provide said sides with a like plurality of slots similarly longitudinally spaced along said body member, said side slots and said top slots being respectively communicated; a screen engaging member comprising a slot engaging section removably inserted through one of said top slots and into communicating side slots, a part of said section underlying said top adjacent said top slot, a pair of fingers each connected at one end to said section and extending longitudinally of said body member respectively along said sides toward and beyond one end of said body member, each of said fingers including a hook at its other end; and lug means carried by and projecting outwardly from said sides adjacent said body member end, said fingers intermediate their ends respectively underlying and engaging said lug means.

6. In a tool for stretching screen wire, a substantially channel shaped body, having a top and depending sides, said top being slotted transversely of said body to provide a plurality of slots longitudinally spaced along said body, said sides being respectively slotted downwardly from said top through a part of the depth of said sides to provide said sides with a like plurality of slots similarly longitudinally spaced along said body member, said side slots and said top slots being respectively communicated; a screen engaging member comprising a slot engaging section removably inserted through one of said top slots and into communicating side slots, a part of said section underlying said top adjacent said top slot, a pair of fingers each connected at one end to said section and extending longitudinally of said body member respectively along said sides toward and beyond one end of said body member, each of said fingers including wire engaging means at its other end; and stop means carried by and projecting outwardly from said sides adjacent said body member end, said fingers intermediate their ends respectively underlying and engaging said stop means.
